UNITED STATES PATENT OFFICE.

WILLIAM G. DUNHAM, OF MOUNT VERNON, NEW YORK, ASSIGNOR TO THE NOESTING PIN TICKET COMPANY, INC., A CORPORATION OF NEW YORK.

PIN-TICKET.

1,152,612.

Specification of Letters Patent.

Patented Sept. 7, 1915.

Application filed August 3, 1914. Serial No. 854,730.

To all whom it may concern:

Be it known that I, WILLIAM G. DUNHAM, a subject of the King of Great Britain, and a resident of Mount Vernon, county of 5 Westchester, State of New York, have invented certain new and useful Improvements in Pin-Tickets, of which the following is a specification.

My invention relates to pin-tickets adapted 10 to be affixed to fabrics or similar materials by passing the pin through them and folding it upon itself to secure the ticket in engagement with the fabric or article to be tagged, and is more especially addressed to 15 that form of pin-ticket in which only a single pin is used. I have found that by using a single pin, and in conjunction with the pin having a notch or cut-out portion in the edge of the ticket, the ticket can very 20 readily be locked in position on the fabric or material to be tagged.

In the drawings, in which like letters represent like parts, Figure 1 is a face view of one form of my ticket; Fig. 2 is an end 25 view; Fig. 3 is a back view; Figs. 4, 5 and 6 are similar views of a modification; and Fig. 7 is a view of my ticket placed on a bolt of fabric to illustrate its use.

In the drawings, A represents the ticket 30 to which the pin is attached. I prefer to use a round-pointed pin made by bending the wire upon itself at the point D, so as to form the round-pointed pin, the pin C being a double-shank pin. The end of the 35 wire opposite the point D of the pin C is then bent as shown in Fig. 2 at E, so as to pass through the ticket along one surface thereof, as shown at the left of Fig. 2, again bent at F, and through to the underside of 40 the ticket, where the free ends are bent upon themselves, as shown at C', so as to engage with the ticket.

As shown in Figs. 1, 2 and 3, the pin normally is parallel to the surface of the ticket. 45 On the edge of the ticket adjacent to the pin, as shown in Figs. 1 and 3, I provide a notch or cut-out portion B so arranged that when the pin C is passed through the fabric to which the ticket is to be attached, the end 50 of the pin is bent upon itself at a point below the edge of the ticket, and in bending it engages with the notch, and when it has been bent the full distance, the point D engages with the upper surface of the ticket 55 and the ticket is locked in engagement with

the fabric. It will be noted that after the wire has been folded upon itself at D the parallel portions of the wire remain substantially in contact with each other, and are not separated, but while in contact with 60 each other they are passed through the ticket twice and the free ends then folded on the under surface of the ticket.

In Figs. 4, 5 and 6, I have shown the preferred form of my invention, having the 65 notch B, the pin C formed by bending a wire upon itself to form a double-shank pin, then bending the portions of the wire opposite the round-pointed end D substantially at right angles to the pin C, but in line with 70 each other, and then passing the free ends through the ticket at the points E, E, and folding them upon the surface of the ticket, as shown at C'-C' in Fig. 4. This form of ticket is much simpler to manufacture 75 owing to the fact that the ends of the wire are bent once and are then folded over upon the ticket, whereas in the ticket shown in Figs. 1, 2 and 3, the wire is bent twice. In 80 this form of ticket, the pin is so placed that after being passed through the fabric and folded, it will lie in the position similar to that shown in Fig. 7.

Having described my invention, what I claim as new and desire to secure by Letters 85 Patent is:

1. In a pinticket, a ticket, a wire bent to form a pin, composed of two members, the members of said pin at a predetermined point being bent to form means engaging with said ticket to hold the pin fixedly secured thereto, wherein portions of said members engage the back face of the ticket and the free ends of said portions pass through said ticket and engage the front face of said ticket, said portions with their free ends lying in substantially the same plane.

2. In a pin ticket, a ticket having a notch in one edge thereof, a pin formed of a wire bent upon itself to form a pin composed of two members, said pin being attached to one face of said ticket adjacent the notch and normally lying throughout its length in a position parallel to and on the underside of said ticket, a portion of the pin composed of two members being adapted when in use to be bent around said ticket in said notch and to engage with the other face of the ticket.

3. In a pin-ticket, a ticket having a notch 110

in one edge thereof, a wire bent to form a pin composed of two members, said members, at a predetermined point, being bent to form means to engage with and to hold the 5 pin fixedly secured to one face of said ticket, a portion of said pin adapted, when in use, to be bent around said ticket in said notch and to engage with the opposite face of said ticket to hold same secured to the material 10 to be ticketed.

4. In a pin-ticket, a ticket having a notch in one edge thereof adapted to receive a pin, a pin fixedly secured to one face of said ticket formed of a wire bent upon itself to 15 form a pin composed of two members, said members, at a predetermined point, being bent in opposite directions away from said pin to lie along one face of the ticket and being again bent to engage the opposite face 20 of said ticket to hold same in engagement therewith.

5. In a pin-ticket, a ticket having a notch in one edge thereof, a pin formed by bending a piece of wire upon itself to form a pin 25

composed of two members, said members, at 25 a predetermined point, being bent at a right angle to the pin, said ticket having openings therein and the ends of said members being bent to pass through said openings and being folded down upon the opposite 30 side of the ticket to hold said pin fixedly secured thereto.

6. In a pin ticket, a ticket, a wire bent to form the body of a pin composed of two members both lying in the same plane, the 35 free ends of said wire passing from one face of said ticket through said ticket and engaging the opposite face thereof and lying at angles to the body of the pin both in a plane parallel to the body of the pin.

In testimony whereof, I have signed my name to this specification, in the presence of two subscribing witnesses.

WILLIAM G. DUNHAM.
